(57) **CLAIM**

The ornamental design for a golf club head, as shown and described.

DESCRIPTION

FIG. 1 is a perspective view of a golf club head showing my new design;

FIG. 2 is a front view thereof;

FIG. 3 is a back view thereof;

FIG. 4 is a top view thereof;

FIG. 5 is a bottom view thereof;

FIG. 6 is a right view thereof;

FIG. 7 is a left view thereof; and,

FIG. 8 is an enlarged cross sectional view taken on line 8-8 of FIG. 3.

The broken lines shown in the figures are for illustrative purposes only and form no part of the claimed design.

The dot-dash broken lines shown in the figures are to indicate a boundary between a claimed design and disclaimed portion, and those are not a part of a claimed design or disclaimed portion.
